CLAIM

I claim the design of a stationary holder for personal electronic communication device (jail cell), as shown.

DESCRIPTION

FIG. 1 is a top view of the stationary holder for personal electronic communication device (jail cell);

FIG. 2. is a right side view thereof;

FIG. 3. is a front view thereof;

FIG. 4. is the left side view thereof;

FIG. 5. is the bottom view thereof;

FIG. 6. is the rear view thereof;

FIG. 7 is a front view thereof indicating the placement of a personal digital assistant (PDA). The door is shown removed for convenience of illustration.

FIG. 8 is a top view thereof with the door in the open position; FIG. 9 is a front view thereof with the door in the open position; and,

FIG. 10 is a front view thereof with the door in the closed position.

The broken line showing of environment in the drawings is included for the purpose of illustrating only and forms no part of the claimed design.
